UNITED STATES PATENT OFFICE.

CHARLES G. SCHENCK, OF COLUMBUS, OHIO.

DESIGN FOR A MEASURING VESSEL.

SPECIFICATION forming part of Design No. 29,619, dated November 8, 1898.

Application filed August 29, 1898. Serial No. 689,812. Term of patent 14 years.

To all whom it may concern:

Be it known that I, CHARLES G. SCHENCK, a citizen of the United States, residing at Columbus, in the county of Franklin and State 5 of Ohio, have invented and produced a new and original Design for Measuring Vessels, of which the following is a specification, reference being had to the accompanying drawings, forming part thereof.

Figure 1 is a side elevation of my newly-designed vessel, and Fig. 2 is a plan view thereof.

The leading or material feature of my design consists in the measuring vessel, comprising the cylindrical body 1, with a top or cover portion 2, which converges to an eccentric-

ally-located opening 3, from about which rises a short flaring neck portion 4, with reference to which said opening is also located eccentrically. The lower portion of the body 1 20 displays a peripheral band 5, while a similar though narrower bead or band 6 encircles the upper portion of the body.

Having described my invention, what I claim as new, and desire to secure by Letters 25 Patent, is—

The design for a measuring vessel as herein shown and described.

CHARLES G. SCHENCK.

In presence of—

C. C. SHEPHERD,

A. L. PHELPS.
